UNITED STATES PATENT OFFICE.

BENJAMIN J. SHIMOTA, OF VESELI, AND GORDON B. CARAWAY, OF ST. PAUL,
MINNESOTA.

EGG-CANDLING APPARATUS.

1,142,535.

Specification of Letters Patent.

Patented June 8, 1915.

Application filed June 8, 1914. Serial No. 843,835.

To all whom it may concern:

Be it known that we, BENJAMIN J. SHIMOTA and GORDON B. CARAWAY, citizens of the United States, residing, respectively, at 5 Veseli, in the county of Rice and State of Minnesota, and at St. Paul, in the county of Ramsey and State of Minnesota, have invented new and useful Improvements in Egg-Candling Apparatus, of which the following is a specification.

Our invention relates to an egg tester, in which a plurality of eggs may be tested currently.

The primary object of our invention is 15 the production of an egg tester, which is adapted to concentrate as much light as possible on the eggs to be tested, and to provide a hood in which the eggs can be viewed during the testing operation without side light 20 decreasing the efficiency of the apparatus.

A further object is to provide a casing which is so constructed that it can be used either by artificial or sun light.

Another object is to provide an adjustable 25 reflector in the casing, which by adjusting may be made to concentrate light originating at different angles to the reflector upon the eggs.

A still further object is to construct the 30 hood with a reflector back of the eggs so that a more complete view of the eggs can be obtained by the observer.

In the accompanying drawing forming 35 part of this specification, Figure 1 is a front elevation of our invention; Fig. 2 is a section on the line X—X of Fig. 1, and Fig. 3 is a section of a detail taken on the line Y—Y, Fig. 2.

In the drawing, A indicates a casing, 40 which is formed with a receptacle B, in which lamps such as C and a reflector D are mounted. Above the receptacle a hood F is formed, which is adapted to shield light, except that passing upwardly through the 45 eggs which are being tested. The casing A is provided with a horizontal partition 2, having a series of apertures 3 in which the eggs are placed and held in upright position. The back of the casing is formed of 50 a removable wall 4, which is adapted to slide up and down and either close or open the receptacle B. The wall 4 is slidably mounted by inturned edges 8 in the channel members 5, which are secured to the ends 6 and 7, 55 of the casing. The lamps C may be mount-

ed in sockets 9 secured on the end walls 6 and 7 of the casing, and when connected with a source of electric current (not illustrated) such as by the conductors 10 are adapted to illuminate the eggs E to be 60 tested, which are held in apertures 3. Placed below the lamps is a reflector D, which is in the form of a plate extending entirely across the receptacle and bent downwardly between its side edges below 65 the lamps. The lower edge of said reflector rests upon the floor of the receptacle and the upper end is supported by a transverse rod 11, which passes freely through vertical slots 12 in the end walls 6 and 7. The ends 70 of said rod are provided with thumb nuts 13, threaded thereon, and when tightened are adapted to engage the end walls of the receptacle and hold the upper edge of the reflector in selected elevation. The reflector 75 is bent downwardly between its upper and lower ends to concentrate rays of light from the lamps upwardly upon the eggs. By loosening the thumb nuts and raising and lowering the reflector as described the angle 80 of reflection can be varied.

The reflector and back 4 may be made of any suitable material, it being preferred that they be provided with inner polished reflecting surfaces, so as to concentrate a maximum amount of light upon the eggs. 85

When it is desired to use light directly from the sun or an outside source instead of lamps C, the back 4 may be raised and the reflector D adjusted at the proper inclination. 90

The hood F is formed by the partition 2, back 14, top 15, and walls 6 and 7, all of said parts being opaque and preferably colored black, on their inner surfaces, so 95 as to intensify the darkness of the space in the hood. The forward lower edge of the hood is also formed with an outwardly and upwardly slanting shade 16, which is formed as an integral part of the front wall 17 of 100 the receptacle. The top wall 15 is also formed with a downwardly and forwardly slanting shade 18. The shades 16 and 18 serve to assist in shielding the eggs which are being tested from outside light and thus 105 intensify light passing upwardly through the eggs. Immediately back of the eggs and secured to the back 14 is a mirror 19, which serves to aid in examining the eggs in the apertures indirectly. 110

In use the eggs to be tested are placed in the apertures 3 and owing to their illumination from the light passing upwardly from within the receptacle any eggs of inferior quality can be instantly detected.

In accordance with the patent statutes, we have described the principles of operation of our invention, together with the apparatus, which we now consider to represent the best embodiment thereof, but we desire to have it understood that the construction shown is only illustrative, and that the invention can be carried out by other means and applied to uses other than those above set forth within the scope of the following claims.

Having described our invention, what we claim as new and desire to protect by Letters Patent is:—

1. An egg tester, comprising, in combination, a casing having a receptacle and a hood above said receptacle, said receptacle and hood being separated by an apertured partition in the apertures of which the eggs to be tested may be placed, a back closing said receptacle and movable thereon to admit sunlight into said receptacle when moved into open position and a reflector having its lower end resting on the floor in said receptacle and its upper end vertically adjustable on the sides of said receptacle, said hood partly enveloping the eggs held

in said apertures to obscure light originating from above said eggs.

2. An egg tester, comprising, in combination, a casing forming two compartments separated in elevation by an apertured partition, in the apertures of which eggs to be tested are adapted to be placed, one of said compartments below said partition forming a lamp receptacle and the other of said compartments forming a hood adapted to shield the eggs held by said apertured partition from outside light, a reflector in said receptacle adapted to concentrate light upwardly upon the eggs held in said apertures, and said hood being formed with overhanging shades surrounding an opening and adapted to assist in shielding light from above the eggs and a mirror back of the eggs held in said apertures adapted to disclose a portion of the eggs to view.

In testimony whereof, we have signed our names to this specification, in the presence of two subscribing witnesses.

BENJAMIN J. SHIMOTA.
GORDON B. CARAWAY.
